CLAIM

We claim the ornamental design for a shower door assemblies, as shown and described.

DESCRIPTION

FIG. 1 is a perspective view of the claimed design; FIG. 2 is another perspective view of the claimed design of FIG. 1; FIG. 3 is a rear view of the claimed design of FIG. 1; FIG. 4 is a front view of the claimed design of FIG. 1; FIG. 5 is a side view of the claimed design of FIG. 1; FIG. 6 is another side view of the claimed design of FIG. 1; FIG. 7 is a top view of the claimed design of FIG. 1; FIG. 8 is a bottom view of the claimed design of FIG. 1; and, FIG. 9 is a detail view of the claimed design of FIG. 1. The ornamental design that is claimed is shown in the drawings as solid lines and surfaces having surface shading. The broken lines in the drawings are for illustrative purposes only and form no part of the claimed design. For example, broken lines formed by equal length dashes show unclaimed portions of the design. Broken lines formed of unequal length dashes (i.e., dash-dot) show boundaries between either claimed and unclaimed portions of the design or between unclaimed and unclaimed portions of the design. The broken away symbols in the drawings indicate that any portion of the article beyond what is shown forms no part of the claimed design.
